UNITED STATES PATENT OFFICE.

WEBB JAY, OF CHICAGO, ILLINOIS.

LIQUID-ELEVATING APPARATUS.

1,244,052.

Specification of Letters Patent.

Patented Oct. 23, 1917.

Application filed July 15, 1915, Serial No. 39,943. Renewed September 17, 1917. Serial No. 191,901.

To all whom it may concern:

Be it known that I, WEBB JAY, a citizen of the United States, residing at Chicago, in the county of Cook and State of Illinois, have invented new and useful Improvements in Liquid-Elevating Apparatus, of which the following is a specification, reference being had to the accompanying drawings, forming a part thereof.

10 The purpose of this invention is to provide an improved construction for lifting liquids from a lower to a higher receptacle by suction, the particular details being designed with special reference to the employment of the device for lifting liquid fuel of an automobile engine from a low level tank to a more or less elevated receptacle from which it may be supplied to the carburetor by gravity. The invention consists in the 15 elements and features of construction shown and described as indicated in the claims.

In the drawings:

Figure 1 is an elevation showing the several parts of this invention in their relative location upon an automobile.

Fig. 2 is a partly diagrammatic view showing in vertical section the main reservoir and the associated and coöperating receptacle and chambers with their connections embodying the invention.

Fig. 3 is an enlarged vertical section of the atmosphere inlet chamber and the adjacent portion of the main reservoir.

Fig. 4 is a view similar to Fig. 3, showing 35 a modified construction.

Fig. 5 is a view similar to Fig. 3, showing a modification in another respect.

Fig. 6 is an end elevation of the upper portion of the main reservoir and atmosphere inlet chamber thereon, showing a gage for indicating the depth of liquid in the main reservoir.

Fig. 7 is a section at the line, 7-7, on Fig. 3, on a large scale, showing the detail 45 construction of the gage seen in Fig. 6.

In the form of the present invention which is shown in Figs. 1, 2 and 3, 1 is the main reservoir which is represented in the usual form of a cylinder placed horizontally on the automobile at the rear part thereof at a comparatively low level. 2 is a fitting mounted thereon containing a chamber, 3, which is valved as hereinafter described for controlling an atmosphere inlet thereto. 4 is a supplemental liquid-receptacle at a higher level than the reservoir, 1,

designed to be at a level suitable for supplying the carburetor by gravity with liquid fuel. 5 is an auxiliary chamber appurtenant to the supplemental liquid receptacle, 4, positioned for receiving the liquid by gravity from said supplemental liquid receptacle, 4, through the discharge tube, 6, having its discharge mouth at a slight inclination so that it is adapted to be closed 60 normally by the check valve, 7, which is opened by gravity flow of liquid from the receptacle, 4, into said auxiliary chamber, 5.

The fitting, 2, is most conveniently made as a casting adapted to be inserted through 70 a circular opening in the upper convex side of the reservoir, 1, which has a flange, 2^a, fitted to the curvature of said reservoir so as to be riveted down tightly thereupon through which the lower end portion of 75 said fitting protrudes a short distance into the reservoir. In the upper part of this fitting there is contained the valved chamber, 3, the bottom of which is preferably

for certain specific purposes hereinafter explained located at or a little above the level 80 of the highest point of the curved upper side of the reservoir 1. This valved chamber, 3, is closed by a top plate, 8, making it air-tight except as to the connections and 85 communications hereinafter described. A liquid fuel feed pipe, 9, extends from the lower part of the interior of the reservoir, 1, for discharge into the upper part of the supplemental receptacle, 4. As a matter of 90

convenience in constructing and assembling this pipe extends down through one side wall of the fitting, 2, which has a vertical passage, 2^b, in reality forming a portion of 95 the pipe, the lower end portion being screwed into the lower end of said vertical passage, and the upper portion being screwed into the upper end thereof. The

cap plate, 8, has an air inlet port, 10, around which on the upper side of the plate there 100 is formed an annular boss, 10^a, for holding a woven wire strainer or screen, 10^b, designed to exclude dust. An air-controlling valve, 11, is seated upon the upper side of 105 its stem, 11^a, extending down through the port for closing the air port, having 110 its stem, 11^a, extending down through the port for operating connections hereinafter described. The plate, 8, has a second aperture at which there is secured a suction connection fitting, 12, having a relatively 110 small aperture, 12^a, for the suction, and adapted for connection with a suction pipe

to lead to any source of suction, as for example the manifold of the engine with which said fitting is shown connected by a pipe, 13. The cap plate, 8, has a third aperture into which there is connected a pipe, 14, which leads to the upper part of the supplemental receptacle, 4, and constitutes a suction and overflow connection between said supplemental receptacle and the 19 valved chamber, 3. From the bottom of the chamber, 3, a liquid discharge nipple, 16, is provided extending down into the cavity of the reservoir, 1, having its lower end slightly deflected so as to present its mouth at a slight inclination so that it is normally closed by gravity by the flap valve, 17, which is opened by gravity flow of the liquid from the valved chamber, 3, back to the reservoir, 1. In the form shown in the 20 earlier figures, a lever, 20, is fulcrumed in the chamber, most conveniently on a lug, 21, which projects down from the cap plate, 8, one arm of said lever being extended to engage the stem, 11^a, of the valve, 11, between stops, 11^b and 11^c, thereon with a range of play between the stops. The opposite arm of the lever carries a small receiver which is preferably in the form of a cup, 22, which is positioned under the discharge end of the overflow and suction pipe, 14, so as to receive the overflow liquid from the supplemental receptacle, 4. Light springs, 25, 26, connect the two ends of a cross-bar, 26, which extends from a depending lug, 27, on the cap plate with the respectively opposite ends of the cross-bar, 28, on the valve engaging arm of the lever, 20, said springs operating to press the end of the lever which is connected with the valve 40 yieldingly toward its fulcrum so that upon being moved from either limit of the range of movement in the lever for operating the air-controlling valve 11, the springs tend to complete the movement to the limit 45 toward which the movement has been started as soon as the line of stress of the spring passes the fulcrum of the lever. Other obvious means may be employed to cause the air controlling valve to complete its movement in either direction with an instantaneous or snap action after a certain initial portion of movement has been forced. In the construction shown, the weight of the valve on the lever which engages it is designed to be sufficient to overbalance the weight of the opposite arm of the lever and the receiver when the latter is empty, but to be overbalanced by the said opposite arm of the lever and the receiver when the latter is filled or nearly filled with liquid fuel which may be discharged into it by overflow from the supplemental receptacle, 4. It will be observed also that in addition to the weight of the 65 receiver the weight of its contents must

overcome the suction from the valve, 11, in order to unseat it. The arm of the lever opposite that which carries the receiver may be weighted if necessary to bring about a proper counter-balance so that the tension 70 of the springs operating in either position of the lever may be substantially negligible.

Upon considering the above described construction, it will be seen that when suction is operating through the pipe, 13, a 75 partial vacuum is created by way of the pipe, 14, in the supplemental receptacle, 4, which will cause liquid to be lifted through the pipe, 9, and delivered into the receptacle, 4, until the same is filled to a point 80 at which such liquid may overflow back through the suction pipe, 14, and be delivered into the receiver, 22, whereupon the air controlling valve, 11, being lifted and opening the air inlet port which is very 85 much larger than the suction port, will practically destroy the partial vacuum existing in the chamber, 3, and in the elevated receptacle, 4, atmospheric pressure passing back through the pipe, 14, to produce a condition of atmospheric pressure in said receptacle, 4, as soon as the contents of the pipe, 14, have been discharged. The receiver, 22, has a small leak-port, 22^a, through which the contents of the receiver 90 will escape into the chamber, 3, and then pass out through the discharge pipe, 16, back into the reservoir, 1. Meanwhile atmospheric pressure, or substantially that, being restored in the supplemental receptacle, 4, the liquid therein will pass out through the pipe, 6, past the check valve, 7, into the auxiliary chamber, 5, from which it will be understood the liquid fuel is supplied to the carburetor in any usual or convenient manner as by the pipe, 30, leading to the carburetor float chamber, 31, shown in outline for indicating its relative position with respect to the other parts described. As soon as the liquid delivered in 105 the receiver, 22, has escaped therefrom through the leak-port, 22^a, the air inlet valve, 11, will be again seated and suction continuously operating through the suction connection, 13, will produce a partial vacuum 110 in the chamber, 3, and in the supplemental receptacle, 4, whereupon the cycle of operation will be repeated.

In Fig. 4 there is shown a modified construction of the means for carrying and 115 operating the air inlet valve, consisting in that the area of the air inlet port and of the valve covering it is designed to be sufficient to cause the suction operating upon the valve when once seated to hold it on 120 its seat firmly enough to require the receiver, 22, to be loaded before it can be forced off its seat, which will cause the port to be opened suddenly as under the control of the spring construction first above de- 125 130

scribed. In the construction shown in Fig. 4 the valve may be connected with the operating lever without any appreciable or considerable range of play, the valve and lever moving substantially together. In this construction the action of the valve in seating is gradual until it comes near to its seat when the suction will pull it suddenly on to its seat with the same effect substantially as produced by the spring action on the other form.

In Fig. 5 there is shown a modification in a different respect, which can be employed with either form of valve action above described. The modification consists in substituting a float for the receiver, 22, which float is caused to move the air valve, 11, for unseating it when the liquid accumulates in the chamber, 3, to a sufficient height to lift the float and cause it to operate the valve. In this construction it will be understood that the lever action on the valve is reversed, that is to say, the float is connected to the lever, 35, on the same arm of the lever which engages the valve stem 11^a for operating the valve 11. The spring connections for shifting the lever past the center are substantially the same as in the other construction. When this method is employed, the discharge of the liquid from the chamber, 3, into the reservoir 1 is desirably reduced so as to be enough less than the cross-sectional area of the aperture of the pipe, 14, to permit the chamber, 3, to fill promptly when the overflow commences through said pipe, 14; but it may still be large enough to permit the chamber, 3, to empty and cause reversal of the valve very promptly so that the refilling action may begin as soon as the supplemental receptacle, 4, can empty into the auxiliary chamber, 5.

When employing the construction described, consisting of the fitting, 2, mounted upon the main reservoir, 1, it is convenient to associate with this fitting means for indicating the level of liquid in the reservoir, 1, thus dispensing with the necessity of a separate fitting for that purpose. To accomplish this the fitting, 2, may have an arm, 2^a, extending down into the reservoir, 1, when the fitting is mounted thereon, and on which there is pivoted a float arm, 40, carrying a small float, 41, at its free end. In the fitting, 2, below the bottom of the valved chamber, 3, there is journaled a rock shaft, 42, which extends out through the wall of the fitting above the reservoir, 1, and, at its outer end carries an index pointer, 44, which operates over a scale, 45, graduated for indicating the depth of the liquid in the reservoir. A link, 46, connecting the float arm, 40, with a lever arm, 47, of the rock shaft, 45, causes the movement of said float arm as the float rises

and falls with the level of the liquid, to rock the shaft, 45, for operating the index pointer, 44.

I claim:

1. In combination with a main reservoir, 70 a valved chamber; a supplemental liquid receptacle; a liquid supply pipe leading from the lower part of the main reservoir to the supplemental receptacle; a suction connection to the valved chamber; a suction and overflow connection between the valved chamber and the supplemental receptacle; the valved chamber having an atmosphere port; a valve controlling said port; a receiver mounted for movement in the valved chamber, and means operatively connecting it with the valve for opening the latter when the receiver is loaded; said receiver being positioned for receiving liquid delivered through the suction and overflow connection for loading said receiver, and means by which the said valve-operating receiver is unloaded of the liquid after operating the valve.

2. In combination with a main reservoir, 90 a valved chamber connected therewith and positioned relatively thereto for draining by gravity thereinto, a check-valve controlling such drainage, such valve being adapted to be opened by gravity and to be seated by 95 suction in the reverse direction flow of the liquid from the chamber into the reservoir; a supplemental liquid receptacle; a liquid supply pipe leading from the lower part of the main reservoir to the supplemental liquid receptacle, a suction connection to the valved chamber; a suction and overflow connection between the valved chamber and the supplemental liquid receptacle; the valved chamber having an atmosphere port; 100 a valve controlling said port; a device movably mounted in said valved chamber, adapted and positioned so as to be moved by the discharge and accumulation of liquid from such suction and overflow connection 105 to a pre-determined amount, and connections by which said device operates the atmosphere-controlling valve.

3. In combination with a main reservoir, 115 a valved chamber; a supplemental liquid receptacle; a liquid supply pipe leading from the lower part of the main reservoir to the supplemental receptacle; a suction connection to the valved chamber; a suction and overflow connection between the valved 120 chamber and the supplemental receptacle; the valved chamber having an atmosphere port; a valve controlling said port; means in said valved chamber for operating said valve upon the discharge and accumulation 125 of a pre-determined amount of liquid from the suction and overflow connections; means for delivering the liquid so discharged and accumulated back into the main reservoir; an auxiliary chamber positioned for receiv- 130

ing liquid discharged by gravity from said supplemental liquid receptacle; a check valve past which such discharge is effected by gravity, such valve being normally seated and adapted to be opened by the gravity and adapted to be seated by suction in the reverse direction.

4. In combination with a main reservoir, a valved chamber mounted thereon and having drainage connection therewith; a valve which controls said drainage connection adapted to be opened by gravity flow of liquid from the valved chamber into the reservoir and to be seated by suction in the reverse direction; a supplemental liquid receptacle at a higher position than the reservoir; a liquid supply pipe mounted rigidly with such valved chamber and extending therethrough without opening thereinto, and leading from the lower part of the reservoir to the supplemental receptacle; a suction connection to the valved chamber; a suction and overflow connection between the valved chamber and the supplemental receptacle; the valved chamber having an atmosphere port; a valve for controlling said port; means mounted movably in the valved chamber for operating said valve and adapted in position for so operating it upon the discharge and accumulation of a predetermined amount of liquid from the suction and overflow connection.

5. In combination with a main reservoir, a valved chamber; a supplemental liquid receptacle; a liquid supply pipe leading from the lower part of the main reservoir to the supplemental receptacle; a suction and overflow connection between the valved chamber and the supplemental receptacle; the valved chamber having an atmosphere inlet port; a valve controlling said port; a lever fulcrumed in said valved chamber and operatively connected to said valve; a receiver carried by said lever positioned for receiving liquid discharge through said suction and overflow connection, adapted when loaded thereby, to cause the lever to move to operate the valve.

6. In combination with a main reservoir, a valved chamber; a supplemental liquid receptacle; a liquid supply pipe leading from the lower part of the main reservoir to the supplemental receptacle; a suction and overflow connection between the valved chamber and the supplemental receptacle; the valved chamber having an atmosphere inlet port; a valve controlling said port; a lever fulcrumed in said valved chamber and operatively connected to said valve; a receiver carried by said lever positioned for receiving liquid discharge through said suction and overflow connection, adapted when loaded thereby to cause the lever to move to

operate the valve; a spring connected to said lever for pressing toward the fulcrum of the lever to cause the lever to move instantaneously to its limit in either direction upon being moved past an intermediate point.

7. In combination with a main reservoir, two chambers one of which is a supplemental liquid receptacle and the other a valved chamber having an atmosphere inlet port; a suction connection to one of said two chambers; a liquid supply pipe leading from the lower part of the main reservoir to the supplemental liquid receptacle; a suction and overflow connection between the atmosphere inlet chamber and the supplemental receptacle; a valve controlling said atmosphere inlet port; means movably mounted in said valved atmosphere inlet chamber for operating said valve, adapted and positioned for operating it upon the discharge and accumulation of a predetermined amount of liquid from the suction and overflow connection, and means for subsequently discharging such liquid back into the main reservoir.

8. In combination with a main reservoir and a relatively elevated supplemental liquid receptacle; a fitting comprising an atmosphere inlet chamber mounted on the main reservoir; means associated with said atmosphere inlet chamber and supplemental receptacle for lifting liquid by suction from the main reservoir to the supplemental receptacle; a float mounted on said fitting and carried thereby within the main reservoir; an index device mounted on the fitting and exposed outside the atmosphere inlet chamber thereof, and operating connections from the float to said index device.

9. In combination with a main reservoir, a valved chamber, a supplemental liquid receptacle; a liquid supply pipe leading from the lower part of the main reservoir to the supplemental receptacle; a suction connection to the valved chamber; a suction and overflow connection between the valved chamber and the supplemental receptacle; the valved chamber having an atmosphere port; a valve controlling said port; a device movably mounted in said valved chamber adapted and positioned so as to be moved by the discharge and accumulation of liquid from such suction and overflow connection to a pre-determined amount, and connections by which said device operates the atmosphere-controlling valve.

In testimony whereof, I have hereunto set my hand at Chicago, Ill., this 22d day of June, 1915.

WEBB JAY.
